H. Lee Shulman

ATTORNEY

UNITED STATES PATENT OFFICE.

JOHN S. KONOP, OF FLUSHING, NEW YORK.

TABLE TOP.

Application filed May 8, 1928. Serial No. 275,983.

The object of the present invention is to provide a table top which shall closely resemble a solid glass or onyx or other stone top, but which may be very cheaply manufactured. The top not only resembles the solid glass and onyx tops but possesses their structural advantages as to rigidity, weight, pleasing appearance, etc.

The invention will be described with reference to the accompanying drawing, in which—

Figure 1 is a perspective view of an embodiment of the invention applied to a table;

Figure 2 is a transverse section on the line 2—2, Figure 1, and

Figure 3 is a longitudinal fragmentary section on the line 3—3, Figure 2.

The top is formed by pressing a sheet metal plate into a flat rectangular or other primary member 1 having flanges 2. Within the structure thus formed and preferably extending transversely of the major length of the structure are disposed spaced tie-bars 3, which bars are rigidly secured to the flanges 2. For this purpose in the embodiment shown in the drawing, the flanges have welded thereto rectangular clips 4 apertured to receive bolts 5 which pass through apertures formed in the tie-bar, in each case, the bolts being threaded to receive nuts 6. As an alternative, the tie-bars may be welded to the clips 4, or they may be formed at their ends with angular surfaces for direct welding to the flanges. The structure is then filled with Portland cement composition, and when the setting of the composition is completed the exposed surface 7 thereof may be finished in any desired manner.

Prior to applying the cement composition a screen 8 may be laid within the structure intermediate the flanges, as for example

upon the tie-bars 3 to aid in binding and reinforcing the cement.

The cement composition may be as desired. In order to vary the weight of the structure, to the cement may be added suitable proportions of wood flour or other light filler material as customary in cement compositions for flooring.

Either prior to or after filling the structure with the cement composition, the metallic surface is coated with a vitreous material which is preferably baked in situ so as to form a porcelain or glass-like external surface.

The completed structure is solid, rigid, of greater strength than a glass or stone structure of the same proportions and has closely similar appearance with a cost very substantially less.

Having described my invention what I claim and desire to secure by Letters Patent is as follows:—

1. As a new article of manufacture, a table top comprising a sheet metal member having side flanges, the flanges being connected by a plurality of tie-bars, the space between the flanges being filled with a rigid, hard, cementitious material, and the exposed portions of the said metallic member and flanges being coated with a vitreous material.

2. As a new article of manufacture, a table top comprising a metallic plate formed with marginal flanges, clips welded to the flanges, tie-bars secured to opposite clips, a cementitious material filling the space intermediate the flanges and covering the tie-bars, and a vitreous covering for the exposed metallic surface of the structure.

In testimony whereof, I have signed my name to this specification.

JOHN S. KONOP.
